AIR TOOL REVERSING LEVER

George R. Curtiss, Chardon, and Earl E. Rush, Mentor,
Ohio, assignors to Cooper Industries, Inc., Houston,
Tex.

Filed Aug. 9, 1974, Ser. No. 495,997

Term of patent 14 years

Int. Cl. D8—03, 99

U.S. Cl. D8—70

FIG. 1 is a perspective view of an air tool reversing lever of our design, showing the reversing lever as it would appear on an air tool which is shown in broken lines for illustrative purposes only;

FIG. 2 is a top plan view;

FIG. 3 is a left side elevational view;

FIG. 4 is a front elevational view;

FIG. 5 is a right side elevational view;

FIG. 6 is a bottom plan view; and

FIG. 7 is a rear elevational view.

We claim:

The ornamental design for an air tool reversing lever, substantially as shown and described.
